W. S. BRADLEY

SWITCH STAND

Filed May 12, 1925

Fig. 1.

William S. Bradley, INVENTOR.

BY

Geo. P. Kimmel.

ATTORNEY.

UNITED STATES PATENT OFFICE.

WILLIAM S. BRADLEY, OF CONNELLSVILLE, PENNSYLVANIA.

SWITCH STAND.

Application filed May 12, 1925. Serial No. 29,764.

To all whom it may concern:

Be it known that I, WILLIAM S. BRADLEY, a citizen of the United States, residing at Connellsville, in the county of Fayette and State of Pennsylvania, have invented certain new and useful Improvements in Switch Stands, of which the following is a specification.

This invention relates to switch stands, but more particularly to adjustable cranks for switch stands, and has for its object to provide, in a manner as hereinafter set forth, a crank for regulating and obtaining a wide area of adjustment with respect to a switch point.

A further object of the invention is to provide, in a manner as hereinafter set forth, an adjustable crank for switch points to compensate for the wear in the parts of the switch stand and for the wear on the rails of the switch, and further to provide a positive lock for the crank arm after adjustment.

Further objects of the invention are to provide, in a manner as hereinafter set forth, an adjustable crank for the purpose referred to, which is simple in its construction, strong, durable, compact, thoroughly efficient in its use, readily adjustable, conveniently installed, and comparatively inexpensive to set up.

With the forgoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a top plan view of a crank arm, in accordance with this invention.

Figure 2 is a side elevation thereof.

Figure 3 is a section on line 3—3, Figure 1.

Referring to the drawings in detail, 1 indicates the vertical shaft of the switch stand and to the lower end of said shaft is secured a crank arm in accordance with

this invention, and which is of the duplex type.

The crank arm comprises a hub 2 for the reception of the lower end of the shaft 1. The body of the hub 2 is formed with pairs of diametrically extending openings 3. The openings of each pair align, and extending through a pair of aligning openings, as well as through the shaft 1, is a hold-fast means for coupling the hub to the shaft. The hold-fast means preferably consists of a headed bolt 4, having a cotter pin 5 extending therethrough, but it is obvious that any suitable means can be employed for coupling the hub and shaft together.

Formed integral with the hub 2 is a pair of oppositely extending cranks 6, 7, which are disposed in the same plane and are arranged between the transverse center and lower end of the hub. As each of the cranks are of the same construction, but one will be described, as the description of one will apply to the other. Each crank consists of a substantially oval-shaped body portion 8 of the desired length and formed with a lengthwise extending slot 9.

The outer side edge throughout of the body portion 8 is toothed, as at 10. Formed integral with the upper and lower faces of the body portion 8 are respectively lengthwise disposed offsets 11, 12, extending from one end to the other end of said body portion, and flush with the inner side edge of the latter. One edge of each offset is toothed, as at 13, and such toothed edge is spaced from the slot 9. Each end of the toothed edge of an offset provides a flat shoulder 14. Associated with either of the cranks 6, 7, is an adjustable locking member 14' of inverted yoke-shape and consisting of a head 15 and a pair of arms 16, 17, spaced a substantial distance from each other. The head 15 is rectangular in contour and the arms 16, 17 depend from the sides of the former. The width of each arm corresponds to the length of the head. The thickness of each arm corresponds to the thickness of an offset 11 or 12.

The locking member straddles the crank from the top thereof and seats in the toothed edge 10 of the crank and the toothed edges of the offsets, and for such purpose the lower face of the head 15 is provided with

a plurality of teeth 18 and the lower end of each arm with a plurality of teeth 19. The teeth 19 on each arm preferably are two in number and are arranged centrally of the lower end of the arm. The engagement of the teeth of the member 14' with the teeth of the crank will lock said member in its adjusted position.

The arms 16 and 17 are provided respectively with openings 20, 21, through which extends a combined pivot and retaining bolt 22 for the switch rod link 23. The link 23 is provided with a bifurcated outer end 24, which straddles the crank and the member 14'. The bifurcated outer end 24 of the link 23 is apertured, as at 25, for the passage of the bolt 22. Extending through the shank of the bolt 22 is a cotter pin 26, which in connection with the head 27 of the bolt 22 pivotally connects the link 23 to the adjustable locking member 14'. The link 23 and the member 14' are adapted to be connected to either one of the cranks 6, 7. The slot 9 is provided for the passage of the bolt 22 whereby the member 14' will be connected to the crank and after connection, said slot 9 permits of the lengthwise adjusting of the member 14' relative to the crank. When the member 14' is adjusted, the link 23 is carried therewith. The member 14' can be adjusted towards the outer or towards the inner end of the crank. After the member 14' has been adjusted, the interengaging of the teeth on the crank with the head 15 and the interengaging of the teeth on the offsets with the arms 16, 17, will lock the member 14' in its adjusted position.

The principal advantage of the invention is in the provision of a positive locking adjustable leverage connection between the crank arm and the switch rod link, as well as to provide for a wide area of adjustment and also to set up a lock between the crank and the adjustable locking member not only 45 interiorly of the latter, but also at its ends, under such conditions providing a positive lock, then furthermore setting up a locking engagement between one side edge and with both faces of the crank, which acts to positively secure the adjustable locking member in adjusted position, and although the preferred embodiment of the invention is as illustrated and described, yet it is to be understood that changes in the details of

construction can be had which will fall within the scope of the invention as claimed.

What I claim is:—

1. In combination, a slotted crank adapted to be secured to the shaft of a switch stand and having one side edge toothed and further having both of its faces toothed adjacent its other side edge, an adjustable locking member having toothed engagement with said toothed edge and toothed engagement with said faces for locking said member in adjusted position, and means for pivotally connecting a switch rod link to said member and for connecting the latter to said crank.

2. A switch arm including a pair of oppositely disposed lengthwise slotted cranks and means for mounting the arm on the shaft of a switch stand, each of said cranks having one side edge toothed and having a lengthwise extended offset on each face thereof, each of said offsets having its inner edge toothed.

3. In combination, a crank adapted to be secured to the shaft of a switch stand and formed with a slot, said crank further provided at one side edge with a series of teeth and on each face with a lengthwise extending toothed offset, an adjustable yoke-shaped locking member straddling said crank and provided with teeth engaging said edge and offsets for locking the member in adjusted position, and means extending through said member and slot for pivotally connecting a switch rod link to said member and for slidably connecting the member to the crank.

4. In combination, a slotted crank provided with means for securing it to the shaft of a switch stand, said crank having one side edge toothed and each of its faces provided with teeth between said slot and the other side edge thereof, an adjustable yoke-shaped locking member straddling said crank and having interiorly arranged teeth engaging with said toothed edge and further having teeth at its lower end engaging with the teeth on the faces of said crank for locking said member in adjusted position, and means extending through said member and slot for pivotally connecting a switch rod link to said member and for slidably connecting the latter to the crank.

In testimony whereof, I affix my signature hereto.

WILLIAM S. BRADLEY.
